ATTORNEY'S.

UNITED STATES PATENT OFFICE.

THEODORE J. MOWRY AND CHESTER B. ROSENBURGH, OF ROME, NEW YORK.

DESIGN FOR A HAME.

SPECIFICATION forming part of Design No. 25,214, dated March 3, 1896.

Application filed November 11, 1895. Serial No. 568,635. Term of patent 3½ years.

To all whom it may concern:

Be it known that we, THEODORE J. MOWRY and CHESTER B. ROSENBURGH, citizens of the United States, residing at Rome, in the county of Oneida and State of New York, have invented and produced a new and original Design for Hames, of which the following is a specification, reference being had to the accompanying drawings, showing the same.

Figure 1 shows a front side view of the hame of our design. Fig. 2 is a cross-section of the same.

This design of hame has as its leading features the convex front and inner sides *c b*,

with a shallow groove *a* running from the lower end of the hame nearly to the upper end, when it runs out, and also having a binding *d* along the outer edge.

What we claim is—

The design of a hame substantially as herein shown and described.

In witness whereof we have affixed our signatures in presence of two witnesses.

THEODORE J. MOWRY.

CHESTER B. ROSENBURGH.

Witnesses:

GEORGE C. CARTER,
PHEBE A. TANNER.
